Primary Examiner — Vy N Koenig*Assistant Examiner* — Elizabeth Anne Glassberg(57) CLAIM

The ornamental design for a pet playpen, as shown and described.

DESCRIPTION

FIG. 1 is a front, top perspective view of a pet playpen, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1; and,

FIG. 10 is an enlarged view of detail "10" identified in FIG. 2.

The dashed broken lines in the figures illustrate portions of the pet playpen that form no part of the claimed design. The dash dot dash broken lines in FIGS. 1, 2, 9 and 10 are for the purpose of illustrating the enlarged view indicators and form no part of the claimed design.
